UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

ARRANGEMENT FOR CONVERTING ACOUSTIC ENERGY INTO ELECTRICAL ENERGY.

Application filed May 29, 1924, Serial No. 716,533, and in Germany June 25, 1923.

My invention relates to arrangements for converting acoustic energy into electrical energy by means of piezo-electric crystals.

An object of the invention is to provide a device which will convert sound waves into electric waves without distortion.

Another object is to provide an arrangement whereby the individual effects of separate sources of sound may be combined to operate any sound receiving device, the relative intensities of the separate sources being separately controlled in their effects on the sound receiving device.

Other objects will be apparent from the following description and claims when considered with the accompanying drawing, in which:

Fig. 1 shows a circuit embodying one form of my invention.

Fig. 2 shows a circuit embodying a modification.

The so-called piezo-electric crystals have, as known, the property of reacting upon mechanical shocks by freeing electric charges and thereby generating an E. M. F.

According to the present invention this phenomenon is used in such a way that when the crystal is fastened to a sound-board of a musical instrument, the charges becoming free in the rhythm of the acoustic vibrations are directly led to the input (grid-cathode) of an incandescent cathode tube. The plate-filament current of this vacuum tube then fluctuates in the same sense as the grid voltage. This arrangement represents a means of converting acoustic energy into electrical energy. A great advantage of this crystal-microphone as compared with the usual carbon microphone is that the sounds are reproduced without distortion.

Fig. 1 of the annexed drawing shows an example of the new arrangement. R is a sound board, for instance, of a violin. K is the crystal provided with two metal coatings, V is an amplifying vacuum tube which, for instance, contains the primary of a transformer C in the plate-filament circuit. Connected to the secondary of transformer C is telephone T.

In order to reproduce orchestral music, one or more crystals may be fastened to the different musical instruments and the separate amplifications can be regulated in such

a way that the music is correctly reproduced.

A circuit for accomplishing this result is illustrated in Fig. 2. R₁, R₂, R₃ and R₄ are the sound boards or sound responsive portions of the different musical instruments. Mounted on each of the sound boards R₁, R₂, R₃ is a crystal K₁, K₂ and K₃ respectively.

In order to increase the effect of one sound board, several crystals may be fastened to the same sound board. Sound board R₄ has two crystals K₄ and K₅ fastened to it.

Each crystal K₁, K₂, K₃, K₄ and K₅ is connected to the input circuit of a separate amplifier tube V₁, V₂, V₃, V₄ and V₅ respectively and the output of each of these tubes connected to the primary of a separate transformer C₁, C₂, C₃, C₄ and C₅ respectively. The secondaries of these transformers are connected in series with a telephone T, so that their joint effects will be impressed on the telephone T. Care should be taken that the transformers are connected so that crystals K₄ and K₅ mounted on the same sound board add in their effects.

If instead of the sound board a suitable membrane is used, this arrangement can be employed for the same purposes as ordinary microphone is taken.

Having described my invention, what I claim is:

1. A device for converting sound waves into electrical impulse undulations, which comprises a plurality of piezo-electric bodies adapted to produce electrical impulse undulations in accordance with the variation in pressure exerted thereon, means associated with certain of said bodies adapted to produce variations in pressure on certain of said bodies in response to sound waves, means associated with certain others of the said piezo-electric bodies adapted to produce variations in pressure on said last mentioned bodies, amplifying means associated with said piezo-electric bodies, and means to render the separate outputs of the several amplifiers additive.

2. A device for converting sound waves into electrical undulations comprising in combination, a plurality of musical instruments, a piezo-electric body associated with each of said instruments and being adapted to generate electrical undulations in accordance with the output of said instruments,

separate amplifying means connected to each of said piezo-electric bodies, and a reproducer adapted to be actuated by said amplifiers.

5. A device for converting sound waves into electrical undulations which comprises, in combination, a plurality of musical instruments adapted to produce mechanical vibrations, a piezo-electric body connected to each of said instruments and adapted to be vibrated by said mechanical vibrations and being also adapted to generate electrical undulations in accordance with the vibrations of the piezo-electric bodies, means to amplify said electrical undulations and means to combine said amplified undulations.
10. 4. In a device for converting acoustical impulses into electrical undulations the combination, of a musical instrument adapted to produce mechanical vibrations, a plurality of piezo-electric bodies connected to said instrument and adapted to be vibrated by the vibrations of said instrument, to produce electrical undulations connected to a separate amplifier each of said bodies adapted to amplify the electrical undulations produced
15. 20. 25.

thereby, and means whereby said amplified impulses may be added together.

5. In a device for converting acoustical impulses into electrical undulations, the combination of a sound producing member having a vibratory element, a plurality of piezo-electric bodies connected to said element and adapted to be vibrated by said element to produce electrical undulations, a separate amplifier connected with each of said bodies, adapted to amplify said electrical undulations and means whereby said amplified undulations may be added together.

6. A device for converting sound waves into electrical undulations comprising in combination, a plurality of sound producing members each having a vibratory element, a piezo electric body associated with each of said elements and being adapted to generate electrical undulations in accordance with the vibration of said elements, separate amplifying means connected to each of said piezo-electric bodies, and a reproducer adapted to be actuated by said amplifiers.

ALEXANDER MEISSNER.
